UNITED STATES PATENT OFFICE.

WILLIAM J. CARROLL, OF WEST HAVEN, CONNECTICUT, ASSIGNOR TO SARGENT & COMPANY, OF NEW HAVEN, CONNECTICUT.

PANIC BOLT.

Application filed February 1, 1924. Serial No. 689,994.

This invention relates to emergency exit bolts or so-called panic bolts of the type which are applied to doors of schoolhouses, theaters, department stores, and other public buildings, for facilitating exit where a fire or the like causes a panic, and are usually applied to one of a pair of swinging doors where one of the doors normally remains closed.

10 The invention relates more particularly to panic bolt mechanism in which the door is provided with bolts adapted to engage keepers or strike-plates in the lintel and floor, respectively, and arranged to be released from the said strike-plates or keepers by the operation of a panic bar on the inner face of the door. In some of its aspects, however, the principles of my invention are not limited to this type of device, although 15 shown in connection therewith in the accompanying drawings.

It is necessary in such structures to provide mechanism whereby the bolts when retracted to permit the door to open will be retained in this retracted position, so that the door will freely close, although usually a spring is provided to urge the bolts normally to protracted position. In some instances, a detent is provided in the bolt case 20 to hold the bolt in retracted position, and a lug or stop is provided on the door frame to coact with the detent when the door is closed to release the bolt and permit its actuation by the spring to protracted position. In the use of such mechanism, however, a person opening the door sometimes depresses the panic bar only far enough to disengage the bolt from the keeper so as to permit the door to open, and not sufficiently 25 far enough to withdraw the bolt completely into the bolt case where it will be engaged by the detent and retained in retracted position. In such case, when the bolt is only partially retracted, and the detent does not become operative, the bolt is immediately protracted by its spring when the panic bar is released, and hence will prevent the door freely closing. The contact of the protracted bolt against the door frame when it is attempted to close the door causes the frame to become mutilated, besides causing the inconvenience of having to lift the panic bar to retract the bolt when it is desired to close the door.

30 One object of my invention is to overcome

the disadvantages referred to, and to provide an improved type of bolt for a panic bolt which will always be maintained in position to allow the door to close.

Another object of my invention is to provide a panic bolt with a bolt mechanism such that the bolt will be retained in any position to which it is retracted to permit the door to open.

It is a further object of the invention to provide a bolt of such shape, in a panic bolt, that once it has been retracted to a sufficient extent to permit the door to open, it will be maintained in the proper position to permit the closing of the door, although the bolt contemplated is one of the dead bolt type.

To these and other ends the invention consists in the novel features and combination of parts to be hereinafter described and claimed.

In the accompanying drawings:—

Fig. 1 is an inside elevational view of the upper part of a door having applied thereto a lock embodying my improvements.

Fig. 2 is a sectional view on line 2—2 of Fig. 1.

Fig. 3 is a view similar to Fig. 2 showing the position of the parts of the panic bolt mechanism as the door is about to be opened.

Fig. 4 is a sectional view of the panic bolt structure when the door is opened.

Fig. 5 is a rear elevational view of the upper bolt case removed from the door.

Fig. 6 is a sectional view on line 6—6 of Fig. 5.

Fig. 7 is a sectional view on line 7—7 of Fig. 6.

In the preferred embodiment of my invention which I have illustrated in the drawings, I have shown at 10 a door provided with a panic bolt mechanism, which includes a panic bar 11 pivoted at one end to an escutcheon 12 and at the other end to a case 13 applied to the door stile. The panic bar 11 is provided with a finger 14 extending into the case 13 and disposed between abutments 15 and 16 connected respectively to the rods 17 and 18 which extend to the bolt mechanism at the upper and lower edges of the door. The bolt controlling mechanism within the case 13 may be of any preferred type, such as that shown in the patent to Voight, No. 1,345,041, dated June 29, 1920, wherein a spring 19 is wound

about a post 20 secured to the case to normally urge both upper and lower bolts to protracted position.

The rod 18 extends upwardly within a case 21, and is connected at its upper end to a bolt stem 22 provided with a head 23 adapted to project from the case and engage the opening 24 in the door lintel to hold the door closed.

10 It will be apparent that once the door is opened and the panic bar 11 released, the spring 19 would at once protract the bolt-head 23, and thus the free closing of the door would be prevented if some means were not 15 employed to retain the bolt in protracted position. To the end that this function may be accomplished in a practical and efficient manner regardless of the extent to which the bolt is retracted, I have arranged 20 a detent which will engage the bolt in any of a number of positions.

The bolt-stem 22 may be slotted or bifurcated, as shown at 25 in Fig. 5, and within this slot may be positioned the 25 plunger 26 of a detent 27 designed to engage the bolt-stem. The plunger 26 may be formed with an interior bore, as shown in Fig. 6, and mounted upon a stud 28 upon the case 21, so that it may normally be urged to operative position by a spring 29. The detent 27 is in the form of a flat base or crosshead secured to the plunger 26, and provided with a longitudinally extending pawl 30 to engage any one of a series of 35 ratchet-teeth 31 on the stem 22 on both sides of the slot 25, so that the bolt will be secured and effectively held in the position to which it is retracted. When the door is closed the plunger 26 is arranged to strike 40 a stop 32 upon the lintel of the door, and is thus moved against the tension of the spring 29 to inoperative position so that the bolt will be protracted by the spring 19 into engagement with its keeper.

45 It may sometimes occur, due to the fact that the teeth 31 must be spaced at least a slight distance apart, that the bolt may be retracted to a sufficient extent to clear the keeper or strike-plate 33, and at such time the pawl 30 would lie between two of the teeth 31 so that when the door is opened the bolt will spring upwardly a slight distance until the pawl engages the tooth directly below it. The bolt in this position might ordinarily be too high to pass the keeper when the door was closed, and hence would strike against the keeper and prevent the free closing of the door.

50 I have obviated this disadvantage by forming the bolt with a bevelled end face 35 such that the height of the bevel is approximately half or more of the distance between two adjacent ratchet-teeth 31. It will be obvious, that if the bolt is retracted until the high edge 36 thereof will pass the keeper

and then springs upwardly to a slight extent after the door is opened until the pawl catches above the next lower tooth 31, when the door is closed the lower edge 37 will be presented to the keeper first and will be sufficiently low to pass thereunder, and the bolt will be cammed down so that there will be no obstruction in the way of the door closing.

55 While I have shown and described a preferred embodiment of my invention, it is to be understood that it is not to be limited to all of the details shown, but is capable of modification and variation within the spirit of the invention and within the scope of the appended claims.

What I claim is:

1. In a panic bolt, a keeper, a bolt adapted to be projected into engagement with the keeper, means normally urging said bolt to protracted position, a series of stops provided upon the bolt, and means to selectively engage said stops to hold the bolt in any one of a plurality of retracted positions said stops being adapted to limit the outward movement of said bolt only.

2. In a panic bolt, a keeper, a bolt adapted to be projected into engagement with the keeper, means normally urging said bolt to protracted position, a series of stops provided upon the bolt, means to selectively engage said stops to hold the bolt in any one of a plurality of retracted positions, said stops being adapted to limit the outward movement of said bolt only and means to render said engaging means inoperative when the door is closed.

3. In a panic bolt, a keeper, a case, a bolt therein adapted to be projected into engagement with the keeper and normally urged to protracted position, means for retracting said bolt, a series of ratchet-teeth on one side of said bolt, and a pawl mounted between the bolt and case to engage any one of said ratchet teeth for the purpose described.

4. In a panic bolt, a keeper, a case, a bolt therein adapted to be projected into engagement with the keeper and normally urged to protracted position, means for retracting said bolt, a series of ratchet teeth on one side of said bolt, a pawl carried by the case adjacent the said side of the bolt to engage any one of said ratchet-teeth, and means for moving said pawl out of engagement with the ratchet-teeth to permit the protraction of the bolt when the door is closed.

5. In a panic bolt, a keeper, a bolt case, a bolt reciprocably mounted therein and normally urged into protracted position to engage the keeper, said bolt being provided with a slotted portion within the case and a detent mounted on the case and extending within said slot to engage the bolt and retain it in retracted position.

6. In a panic bolt, a keeper, a bolt case, a bolt reciprocably mounted therein and normally urged into protracted position to engage the keeper, said bolt being provided with a slotted portion within the case and a detent mounted on the case and extending within said slot to engage the bolt and retain it in retracted position, said detent having a plunger projecting from the case and adapted for engagement to release the bolt to permit the protraction thereof.
7. In a panic bolt, a keeper, a bolt adapted to be projected into engagement with the keeper and normally urged toward protracted position, means for retracting the bolt, said bolt being provided with a plurality of stops, a detent to engage any one of said stops to secure the bolt in a retracted position, said bolt being provided with a head having a bevelled face for the purpose described.
8. In a panic bolt, a keeper, a bolt adapted to be projected into engagement with the keeper and normally urged toward protracted position, means for retracting the bolt, said bolt being provided with a plurality of spaced stops, a detent to engage any one of said stops to secure the bolt in a retracted position, said bolt being provided with a head having a bevelled face for the purpose described, the pitch of said bevel being less than the distance between two adjacent stops.
9. In a panic bolt, a keeper, a bolt adapted to be projected into engagement with the keeper and normally urged toward protracted position, means for retracting the bolt,
- 5 said bolt being provided with a plurality of ratchet-teeth, a detent to engage any one of said ratchet-teeth to secure the bolt in a retracted position, said bolt being provided with a head having a bevelled face.
10. In a panic bolt, a casing, a bolt slidably mounted therein, the stem of said bolt being bifurcated, and means for dogging said bolt against movement, comprising a plunger slidably mounted in the casing between the bifurcated parts of said bolt and provided with a crosshead adapted to engage said parts.
11. In a panic bolt, a casing, a bolt slidably mounted therein, the stem of said bolt being bifurcated, and means for dogging said bolt against movement, comprising a plunger slidably mounted in the casing between the bifurcated parts of said bolt, and provided with a crosshead adapted to engage said parts in any one of a plurality of positions to hold the bolt in retracted position within the casing.
12. In a panic bolt, a case, a bolt slidably mounted in the case and having a slotted portion, a series of teeth on the parts of said bolt on the sides of the slot, a stud on the bolt case adjacent said tooth portion, a spring pressed plunger mounted on said stud and projecting through said slot and the opposite side of the case, and means on said plunger to engage the bolt teeth on both sides of the slot.

In witness whereof, I have hereunto set my hand on this 29 day of Jany., 1924.

WILLIAM J. CARROLL.
